UNITED STATES PATENT OFFICE.

HORACE W. ULRICH, OF EAST ORANGE, NEW JERSEY, ASSIGNOR TO WESTERN ELECTRIC COMPANY, INCORPORATED, OF NEW YORK, N. Y., A CORPORATION OF NEW YORK.

TELEPHONE SYSTEM.

1,408,046.

Specification of Letters Patent. Patented Feb. 28, 1922.

Application filed July 11, 1919. Serial No. 310,042.

To all whom it may concern:

Be it known that I, HORACE W. ULRICH, a citizen of United States, residing at East Orange, in the county of Essex, State of New Jersey, have invented certain new and useful Improvements in Telephone Systems, of which the following is a full, clear, concise, and exact description.

This invention relates to telephone systems, and more particularly to such systems employing long telephone transmission lines equipped with amplifiers or repeaters.

The primary object of this invention is the provision of a telephone system embracing telephone transmission lines equipped with amplifiers for amplifying either talking or signaling currents or both, the transmission efficiency or equivalent of which will be maintained substantially constant regardless of variations in conditions affecting the electrical characteristics of the transmission lines.

It is well known that the transmission equivalent or efficiency of a telephone transmission line varies due to many different causes. Chief among the many causes contributing to variations in the transmission efficiency of a telephone transmission line may be mentioned variations in resistance, capacity and inductance of the line and associated apparatus due to variations in voltages and temperature.

The present invention contemplates the elimination of the difficulties heretofore encountered due to such variations by compensating therefor by varying some adjustable element or elements of the transmission line.

In attaining the objects of the present invention, there is associated with a transmission line terminating at widely separated stations control apparatus conditioned for operation upon the actuation of a switching device at one end of the transmission line and operating upon the restoration of the switching device to normal condition. The operation of the control apparatus disconnects the transmission line from the terminating apparatus, forms a loop circuit thereof, connects a responsive device with the loop circuit for thereafter controlling the control apparatus, and simultaneously sets the amplifiers associated with the transmis-

sion line so that the amplification thereof is greater than the attenuation of the loop circuit thereby causing the circulation of power in the loop circuit. The responsive device is operated by the power circulating in the loop circuit, and causes the control apparatus to gradually decrease the amplification of the amplifiers until the circulation of power ceases, whereupon the responsive apparatus ceases to respond restoring the control apparatus to normal condition.

For a more complete understanding of the present invention, reference should be had to the following description considered in connection with the accompanying drawings, which with Figs. 1, 2 and 3 thereof when placed end to end with Fig. 1 at the left, 70 illustrate one embodiment thereof. For convenience, like apparatus at the two terminating stations will be designated by the same reference characters, that at one station being without and that at the other 75 station with primes.

There is shown in the drawings a four-wire repeater circuit of the type disclosed in the Van Kesteren Patent, No. 1,189,411, July 4, 1916, which terminates at and interconnects two widely separated offices or stations A and C. This four-wire circuit, which comprises a pair of transmission lines E and W for transmitting in opposite direction, extends through an intermediate 85 station B at which are located amplifiers or repeaters RE and RW connected in the respective lines E and W of the four-wire circuit. The amplification or gain of the amplifiers RE and RW is controlled by adjustable potentiometers PE and PW associated with the input circuits of the respective amplifiers. The adjustment of these potentiometers is controlled by an automatic switch controlled from the offices A and C 95 over a simplex circuit built partly upon the transmission line E and partly upon the transmission line W. This automatic switch comprises rotatable contact arms a, b, c and d mounted upon a common shaft the step-by-step advance of which is controlled by a self-interrupting motor magnet MM. Each of the contact arms when rotated successively engages stationary contacts, those associated with the contact arms a and b co-operating therewith to control the adjust-

ment of the potentiometers PE and PW, those associated with contact arm *c* controlling the circuit of the motor magnet MM and those associated with contact arm *d* controlling signal lamps 76 and 77 and a buzzer 79. At the offices A and C, the four-wire transmission circuit is terminated through two-wire terminating circuits T and T' respectively, the transmission lines E and W of the four-wire transmission circuit being associated with the terminating circuits T and T' through the windings of the repeating coils 5 and 5' and the auto transformers 6 and 6'. At the office A there is provided a cord circuit D for establishing connections with the two-wire terminating circuit T of the four-wire circuit and a similar cord circuit D' located at the office C for establishing connections with the two-wire terminating circuit T' of the four-wire circuit thereat. The apparatus shown in Fig. 1 is shown at the office A, that in Fig. 2 at the office B and that in Fig. 3 at the office C.

The operator at the office A, desiring to establish connection with the office C by way of the four-wire transmission circuit, inserts plug 10 of cord circuit D into jack 11 of the terminating circuit T, thereby causing the operation of relays 12 and 13. Slow release relay 14 operates upon the energization of relay 13, opening a contact in a normally closed simplex circuit, thereby causing the release of relays 15, 16, 17, 16' and 15' connected in this simplex circuit. This simplex circuit may be traced from grounded positive battery through the contact of relay 14, windings of relays 15 and 16, then in parallel, the line windings of repeating coil 45, the two-line-wires of transmission line W and the secondary windings of output coil 64, winding of relay 17, left-hand normal contact of relay 72, then in parallel through the secondary windings of output coil 44, the two line-wires of transmission line E and the line windings of repeating coil 45', windings of relays 16' and 15' and contact of relay 14' to grounded negative battery. Upon the release of relay 15, relay 18 operates over a circuit from battery through resistance 19, winding and left-hand normal contact of relay 18 and the back contact of relay 15 to ground. Relay 18 in operating opens its normal contacts and closes its alternate contacts establishing a locking circuit for itself through its left-hand alternate contact to ground. Upon the closure of the right-hand alternate contact of relay 18 an energizing circuit for relay 20 is prepared. The release of relay 17 causes the energization of the slow release relay 21 which, in closing its left-hand contact, closes the filament circuit of the amplifiers RE and RW and an amplifier 25. With the output circuit of amplifier 25 is associated a relay 26. The release of relay

15' causes the energization and locking up of relay 18' which prepares an energizing circuit for relay 20'.

In order to signal the office C the operator at the office A may now actuate ringing key 27, thereby causing the energization of ringing response relay 28 over a circuit from a source of 16 cycle ringing current 29 through the lower alternate contact of the ringing key 27, ring contacts of the plug 10 and the jack 11, lower normal contact of ringing relay 30, lower winding of relay 28, condenser 31, upper winding of relay 28, upper normal contact of ringing relay 30, tip contacts of the jack 11 and the plug 10 and the upper alternate contact of ringing key 27 to ground. Relay 28 in operating causes the deenergization of a normally energized relay 32. Relay 32 in releasing its armature causes the operation of relays 33 and 34 over a circuit from battery through the windings of these two relays in series and the contact of relay 32, to ground. Relay 33 in operating disconnects the transmission line W from the terminating circuit T. The operation of relay 34 causes the energization of ringing relay 35 which connects a source of 133 cycle ringing current with the transmission line E which traverses the primary winding of input coil 40. Through the inductive action of the input coil 40 signaling current is admitted to the input circuit of the amplifier RE, amplified thereby into the output circuit of the amplifier and causes the operation of ringing response relay 41 connected in the output circuit. Ringing response relay 41 in opening its right hand contact causes the release of a normally energized slow release relay 42. This relay 42 in opening its normal contact opens a contact in the shunt of the potentiometer PE and in closing its left-hand contact connects a condenser 43 in parallel with the primary winding of the input coil 40. The capacity of this condenser 43 is such as to form with the primary winding of the input coil 40 when connected in parallel therewith, a loop circuit tuned to the frequency of the signaling current. This tuned circuit serves to transmit most efficiently to the amplifier RE the frequencies of the signaling current. The amplified signaling current in the output circuit of the amplifier RE traverses the primary windings of the output coil 44 and is repeated thereby into the line E extending to the station C and is repeated thereat through the windings of simplex coil 45' and the windings of the auto-transformer 6', causing the energization of ringing response relay 46'. The energization of ringing response relay 46' causes the deenergization of a normally energized relay 47'. Upon the closure of the contact of this relay 47', relays 33' and 49' operate in series. The former (relay 33') disconnects line E from the

- terminating circuit T' and the latter (relay 49) causes the energization of ringing relay 30'. The operation of this ringing relay 30' causes the operation of ring-up relay 51' 5 over a circuit from a source of 16 cycle ringing current 52' through the lower alternate contact of ringing relay 30', lower contact of the jack 11', left-hand winding of relay 51', condenser 53', upper contact of jack 11' 10 and the upper alternate contact of ringing relay 30' to ground. Relay 51' upon being energized completes a locking circuit through the right-hand winding and normal contact of relay 13' to ground. Signal lamp 15 54' is in parallel with the locking winding of relay 51' and is lighted upon the closure of this locking circuit. The lighting of this lamp 54' serves as a line signal to the operator at the office C. 20 Upon the restoration of the ringing key 27 to normal position, ringing response relay 28 releases its armature causing the energization of relay 32, whereupon relays 33, 34 and 35 release. Upon the release of ringing relay 35, ringing response relay 41 is deenergized causing the energization of relay 42, which restores the input circuit of the amplifier RE to normal condition. Also upon the release of ringing relay 35 ringing 25 response relay 46' is also deenergized. Relay 47' thereupon operates causing the release of relays 33', 49' and 30'. The operator at the office C upon observing the lighted condition of the lamp 54' 30 may insert plug 10' of the cord circuit D' into the jack 11', thereby operating relays 12' and 13'. Relay 14' operates upon the energization of relay 13' and introduces another break in the simplex circuit including 35 the relays 15, 16, 17, 16' and 15'. The opening of the normal contact of relay 13' causes the release of relay 51' and the extinguishment of the lamp 54'. The operators may 40 actuate the listening keys 55 and 55' connecting the respective telephone sets in circuit, and may then converse. It is to be understood, of course, that the cord circuits D and D' provided at the offices A and C may and usually do form connecting links between the four-wire circuit and telephone 45 lines terminating at the respective offices A and C. These lines, however, and the remaining portion of the cord circuits D and D' form no part of the present invention and 50 are therefore not shown in the drawings. At the conclusion of the conversation between the operators or between the subscribers at the stations on the lines joined through the cord circuits and the four-wire repeater 55 circuit, the operator at the office C may give a disconnect signal to the operator at the office A and thereupon disconnect the cord circuit D' from the two-wire terminating circuit T' of the four-wire circuit. In giving 60 the disconnect signal the operator at the office C actuates ringing key 27' connecting a source of 16 cycle ringing current 29' in circuit to cause the energization of ringing response relay 28'. Relay 32' thereupon releases causing the energization of relays 33' and 34'. The former disconnects the transmission line E from the terminating circuit T' and the latter causes the energization of ringing relay 35' which connects a source of 133 cycle ringing current with transmission line W, causing the energization of ringing response relay 61 at the station B and ringing response relay 46 at the station A. The energization of ringing response relay 61 causes the deenergization of a normally energized slow release relay 62 which opens the shunt of the potentiometer PW from across the input circuit of the amplifier RW and connects a resonating condenser 63 in parallel relation with the primary winding 65 of the input coil 60. The energization of ringing response relay 46 causes the release of relay 47, whereupon relays 33 and 49 operate. The operation of the former disconnects the transmission line W from the 70 terminating circuit T and the latter causes the energization of ringing relay 30. Relay 30 in energizing connects a source of 16 cycle ringing current 52 in circuit with the energizing winding of ring-up relay 56. 75 The relay 56 thereupon locks up over a circuit from battery through the contact of relay 12, right-hand winding of relay 56 and contact thereof to ground. Supervisory lamp 57 also lights upon the energization 80 of relay 56 and serves as a disconnect signal to the operator at the office A. The restoration of the ringing key 27' to normal position causes the release of ringing response relay 28' whereupon relay 32' operates releasing relays 33', 34' and 35'. 105 133 cycle ringing current is thereupon disconnected from the transmission line W causing the release of the ringing response relays 61 and 46. The release of the former causes the energization of relay 62 which restores the input circuit of the amplifier RW to normal position. The release of ringing response relay 46 causes the energization of relay 47 whereupon relays 33, 49 and 30 release 110 restoring the apparatus of the terminating circuit T to normal position. 115 The disconnection of the cord circuit D' from the terminating circuit T' by the removal of the plug 10' from the jack 11' 120 causes the release of relays 12' and 13'. The release of relay 13' causes the deenergization of slow release relay 14'. This relay 14' and its companion relay 14 at the office A are made slow in releasing to prevent 125 false operation of the relays in the simplex circuit due to any momentary energization and release of the sleeve relays. The operator at the office A observing the lighted condition of the supervisory lamp 130

57 may withdraw the plug 10 from the jack 11 whereupon relays 12 and 13 release. Relay 12 in releasing opens the locking circuit of relay 56, whereupon the lamp 57 is extinguished. The release of relay 13 causes the deenergization of slow release relay 14.

Relays 14 and 14' are both deenergized at this time so that the simplex circuit is re-established causing the relays 15, 16, 17, 16' and 15', connected therein, to be energized. Upon the energization of relays 15 and 16, relay 20 operates over a circuit from battery through the winding of relay 20, normal contact thereof, right-hand alternate contact of relay 18, contact of relays 16 and the normal contact of relay 15 to ground. Relay 20 in operating completes a locking circuit for itself from battery through its winding and inner right-hand alternate contact and the contact of relay 39 to ground. Relay 20 in operating also causes the operation of disconnecting relays 36 and 37 which disconnect the lines E and W from the windings of the repeating coil 5 and the auto-transformer 6 and connects these two lines together through a pair of looping conductors 38. The lower movable contact of relay 37 is in parallel with the normal contact of relay 14, so that the energization of relay 14 by the insertion of the plug 10 in the jack 11 will not disturb the simplex circuit while relays 36 and 37 are energized. While these operations are taking place at the office A, similar operations are going on at the office C. That is, the energization of relays 15' and 16' causes relay 20' to energize and lock up over circuits similar to those traced in connection with relay 20. Relay 20' in operating causes the operation of disconnecting relays 36' and 37' which disconnect the lines E and W from the windings of the auto-transformer 6' and the repeating coil 5' and connects these lines together by means of a pair of looping conductors 38'.

Simultaneously with the above described operations taking place at the stations A and C, certain operations are taking place at the station B. The energization of relay 17 closes the normal contact thereof before the right-hand contact of slow release relay 21 is opened so that start relay 70 is energized over a circuit from battery through the winding of start relay 70, contact of slow release relay 71, right-hand contact of slow release relay 21 and the normal contact of relay 17 to ground. Relay 21 when fully released opens the filament circuit of the amplifiers and also opens the energizing circuit of start relay 70. Before this energizing circuit is opened, however, a locking circuit for start relay 70 is completed from battery through the winding of relay 70, left-hand contact thereof, right-hand normal contact of relay 72 and the winding of relay 73 to ground. Relay 73 operates over this circuit

bridging the input circuit of the amplifier 25 across the transmission line E and closing a circuit through the polarizing windings of singing response relay 26. This circuit may be traced from battery through resistance 74, outer right-hand and left-hand windings of singing response relay 26 and the left-hand contact of relay 73 to ground.

Upon the operation of relay 70, as previously described, a circuit is completed through the motor magnet MM which thereupon advances the contact arms *a*, *b*, *c* and *d* until the contact arm *c* engages the first contact connected with the terminal of the winding of relay 72, whereupon this relay immediately operates. Relay 72 in operating opens its left-hand contact, which is in the simplex circuit, thereby causing the release of relays 15, 16, 17, 16' and 15' included in this simplex circuit. The closure of the alternate contact of relay 72 causes the energization of slow release relay 71 over a circuit from battery through the winding of relay 71, alternate contact of relay 72 and the winding of relay 73 to ground. Relay 72 in opening its right-hand normal contact opens the locking circuit of start relay 70, while slow release relay 71 upon energizing opens the original energizing circuit of the start relay 70. Start relay 70 therefore releases opening the operating circuit of the motor magnet MM. The motor magnet MM therefore ceases to advance the contact arms *a*, *b*, *c*, and *d* of the automatic switch. The release of relay 17 upon the opening of the simplex circuit at the left-hand contact of relay 72, causes the energization of the slow release relay 21 which at its left-hand contact closes the filament circuit of the amplifiers RE, RW and 25. The deenergization of relay 15 establishes a short circuit for the winding of relay 18 which may be traced from the upper terminal of the resistance 19 through the outer left-hand contact of relay 20 and the alternate contact of relay 15 to ground. Relay 18 thereupon releases its armatures preparing at its right-hand normal contact an energizing circuit for relay 39. In a similar manner the release of relay 15' establishes a short circuit for the winding of relay 18' causing the release thereof. Relay 18' then in closing its left-hand normal contact prepares an energizing circuit for relay 39'.

When the contact arm *c* engages the first contact connected with the winding of relay 72, the contact arms *a* and *b* are connected to the extreme left and right-hand effective contacts of the respective potentiometers PE and PW. With this setting of the potentiometers, amplifiers RE and RW produce the highest degree of amplification which is greater than the attenuation of the loop circuit. A circulation of power over the loop circuit therefore results. The input circuit

- of the amplifier 25 is connected in bridge of this trunk so that the relay 26 connected in the output circuit of the amplifier 25, is operated by the power circulating in the loop 5 circuit and opens its contact thereby opening the circuit of relay 81 which releases. The closure of the left-hand contact of this relay 81 connects a constantly driven interrupter 82 in circuit with the winding of the motor 10 magnet MM, whereupon this motor magnet MM becomes effective to advance the contact arms *a*, *b*, *c* and *d* step-by-step in the direction of the arrows. The closure of the right-hand contact of relay 81 establishes a holding 15 circuit for relay 72 so that this relay does not release upon the movement of the contact arm *c* out of engagement with the contacts connected with the terminal of the winding of relay 72. The contact arms *a*, *b*, *c* and *d* 20 are advanced step-by-step, the contact arms *a* and *b* gradually adjusting the potentiometers PE and PW thereby gradually reducing the amplification of the amplifiers RE and RW until the circulation of power ceases. 25 As the circulation of power ceases, relay 26 ceases to respond and closes its contact causing the energization of relay 81 which then opens the operating circuit of the motor magnet MM which ceases to advance the 30 contact arms. The opening of the energizing circuit of relay 72 at the right-hand contact of relay 81 causes the deenergization of relay 72 which opens its alternate and closes its normal contacts. Upon the closure of the 35 left-hand contact of relay 72, the simplex circuit is reestablished causing the reenergization of relays 15, 16, 17, 16' and 15'. Relay 71 is slow in releasing so that upon the opening of its energizing winding at the 40 alternate contact of relay 72 the contact of relay 71 is not closed until after the opening of the contacts of slow release relay 21 whose energizing circuit is opened by the energization of relay 17 in the simplex circuit. In 45 this manner the energizing circuit of start relay 70 is not reestablished upon the deenergization of relay 72. The deenergization of relay 72 also causes the deenergization of relay 73 which opens the polarizing circuit 50 of relay 26 and disconnects the associated amplifier 25 and the relay 26 from the loop circuit formed by the transmission lines E and W. 55 The energization of relays 15 and 16 in the simplex circuit causes the operation of relay 39 over a circuit from battery through the winding of relay 39, outer right-hand alternate contact of relay 20, right-hand normal contact of relay 18 and the normal contacts 60 of relays 16 and 15 to ground. Relay 39 in operating opens the locking circuit of relay 20 which releases causing the deenergization of disconnect relays 36 and 37 and the deenergization of relay 35, whereupon all apparatus at the station A is restored to its 65 normal condition. In a similar manner the energization of relays 15' and 16' in the simplex circuit at the station C causes the operation of relay 39' which opens the locking circuit of relay 20'. Relay 20' in releasing causes the deenergization of disconnect relays 36' and 37' and the release of relay 35'. All apparatus at the station C is therefore restored to its normal condition. 70 In adjusting the potentiometers PE and PW to gradually reduce the amplification of the associated amplifiers RE and RW until the circulation of power in the loop circuit ceases, the contact arms may be stopped in such position that the contact arm *d* engages 75 one of the extreme right-hand or extreme left-hand contacts connected to the respective signal lamps 76 and 77, should the contact arms be stopped in such a position one or the other of the lamps would be lighted 80 and the relay 78 operated. The buzzer 79 would also operate. The lighting of one or the other of the lamps and the operation of the buzzer would serve as a signal to the attendant at the station B, indicating an abnormal 85 adjustment of the potentiometers. This would indicate that there is some condition in one or the other of the transmission lines E or W requiring attention on the part of the attendant. The lamp 76 is lighted and the buzzer 79 operated each time the potentiometers are set for the highest degree of gain of the amplifiers RE and RW. The length of time the lamp is lighted and the buzzer is operated is very short and merely 90 indicates that the potentiometers are being 95 adjusted. It is the continued lighting of one of the lamps and the operation of the buzzers which indicate an abnormal setting of the 100 potentiometers. 105 The actuation of either of the keys 58 and 58' provided at the respective stations A and C and the restoration of the actuated key to normal conditions causes the control apparatus to loop the transmission lines together, 110 to connect therewith the relay 26 and to adjust the potentiometers in the same manner as when a connection is built up over the four wire circuit and then broken down as described above. 115 What is claimed is: 1. In a telephone circuit, in combination, a four-wire transmission circuit including a pair of transmission lines for transmitting in opposite directions, amplifiers for the 120 transmission lines, an automatic switch, means under control of the automatic switch for determining the amplification of the amplifiers, means for interconnecting the ends of the transmission lines to form a loop 125 circuit thereof and for simultaneously advancing the switch to a predetermined position thereby setting the amplifiers for the highest degree of amplification so that power circulates over the loop circuit, power 130

- responsive means for advancing the switch until the circulation of power ceases, and means responsive to interruption of the circuit for connecting said power responsive 5 means with said loop circuit.
2. In a telephone circuit, in combination, a four-wire transmission circuit including a pair of transmission lines for transmitting in opposite directions, amplifiers for the 10 transmission lines, an automatic switch, means under control of the automatic switch for determining the amplification of the amplifiers, means for interconnecting the ends of the transmission lines to form a loop 15 circuit thereof and for simultaneously advancing the switch to a predetermined position thereby setting the amplifiers for a degree of amplification greater than the attenuation of the transmission lines so that 20 power circulates over the loop circuit, power responsive means for advancing the switch to reduce the amplification of the amplifiers until the circulation of power ceases, and means responsive to interruption of the 25 circuit for connecting said power responsive means with said loop circuit.
3. In a telephone system, in combination, a four-wire transmission circuit including a pair of transmission lines for transmitting in opposite directions, amplifiers for the 30 transmission lines, an automatic switch, means under control of the automatic switch for determining the amplification of the amplifiers, means for interconnecting the 35 ends of the transmission lines to form a loop circuit thereof and for advancing the switch to a predetermined position thereby setting the amplifiers for the highest degree of amplification so that power circulates over 40 the loop circuit, and means controlled by current flowing over portions of both transmission lines and responsive to the power circulating in the loop circuit for advancing the switch until the circulation of power 45 ceases.
4. In a telephone circuit, in combination, a four-wire transmission circuit including a pair of transmission lines for transmitting in opposite directions, amplifiers for the 50 transmission lines, an automatic switch, means under control of the automatic switch for determining the amplification of the amplifiers, means controlled over a circuit including portions of both transmission lines 55 for interconnecting the ends of the transmission lines to form a loop circuit thereof and for advancing the switch to a predetermined position thereby setting the amplifiers for the highest degree of amplification so that 60 power circulates over the loop circuit, power responsive means for advancing the switch until the circulation of power ceases, and means responsive to interruption of the circuit for connecting said power responsive 65 means with said loop circuit.
5. In a telephone system, in combination, a four-wire transmission circuit interconnecting two terminal stations and including a pair of transmission lines for transmitting in opposite directions, amplifiers for 70 the transmission lines located at an intermediate station, means for interconnecting the ends of the transmission lines to form a loop circuit thereof, means at the intermediate station controlled from a terminal station for increasing the amplification of the amplifiers so that power circulates over the loop circuit, power response means at the intermediate station, means thereat controlled from a terminal station for connecting the power response means with the loop circuit, and means controlled by the power response means for gradually decreasing the amplification of the amplifiers 75 until the circulation of power ceases. 80
6. In a telephone system, in combination, a four-wire transmission circuit interconnecting two terminal stations and including a pair of transmission lines for transmitting in opposite directions, amplifiers for the 85 transmission lines located at an intermediate station, means for interconnecting the ends of the transmission lines to form a loop circuit thereof, means at the intermediate station for increasing the amplification of the amplifiers so that power circulates over the loop circuit, power response means at the intermediate station, means thereat controlled from a terminal station for connecting the power response means with the loop circuit, and means controlled by the power response means for gradually decreasing the amplification of the amplifiers until the circulation of power ceases. 85
7. In a telephone system, in combination, a four-wire transmission circuit interconnecting two terminal stations and including a pair of transmission lines for transmitting in opposite directions, amplifiers for the 90 transmission lines located at an intermediate station, means for interconnecting the ends of the transmission lines to form a loop circuit thereof, means at the intermediate station for increasing the amplification of the amplifiers so that power circulates over the loop circuit, power response means at the intermediate station, means thereat controlled from a terminal station for connecting the power response means with the loop circuit, and means controlled by the power response means for gradually decreasing the amplification of the amplifiers 95 until the circulation of power ceases. 100
8. In a telephone system, in combination, a four-wire transmission circuit interconnecting two terminal stations and including a pair of transmission lines for transmitting in opposite directions, amplifiers for the 105 transmission lines located at an intermediate station, means controlled over a circuit including portions of both transmission lines for interconnecting the ends of the transmission lines to form a loop circuit thereof, means at the intermediate station for increasing the amplification of the amplifiers so that power circulates over the loop circuit, power response means at the intermediate station, means thereat controlled over the circuit including portions of both 110 transmission lines for connecting the power response means with the loop circuit, and means controlled by the power response means for gradually decreasing the amplification of the amplifiers until the circulation of power ceases. 115
9. In a telephone system, in combination, a four-wire transmission circuit interconnecting two terminal stations and including a pair of transmission lines for transmitting in opposite directions, amplifiers for the 120 transmission lines located at an intermediate station, means controlled over a circuit including portions of both transmission lines for connecting the power response means with the loop circuit, and means controlled by the power response means for gradually decreasing the amplification of the amplifiers until the circulation of power ceases. 125
10. In a telephone system, in combination, a four-wire transmission circuit interconnecting two terminal stations and including a pair of transmission lines for transmitting 130

- ting in opposite directions, amplifiers for the transmission lines located at an intermediate station, power response means at the intermediate station, means controlled over a 5 circuit including a portion of both transmission lines for interconnecting the ends of the transmission lines to form a loop circuit thereof and for simultaneously connecting thereto the power response means, means 10 at the intermediate station for increasing the amplification of the amplifiers so that power circulates over the loop circuit, and means therefor controlled by the power response means for gradually decreasing the 15 amplification of the amplifiers until the circulation of power ceases.
9. In a telephone system, in combination, a four-wire transmission circuit interconnecting two terminal stations and including 20 a pair of transmission lines for transmitting in opposite directions, amplifiers for the transmission lines located at an intermediate station, means for interconnecting the ends of the transmission lines to form a loop 25 circuit thereof, means at the intermediate station and controlled from a terminal station over a circuit including portion of both transmission lines for increasing the amplification of the amplifiers so that power 30 circulates over the loop circuit, and means at the intermediate station responsive to such circulating power for gradually decreasing the amplification of the amplifiers until the circulation of power ceases.
- 35 10. In a telephone system, in combination, a four-wire transmission circuit interconnecting two terminal stations and including a pair of transmission lines for transmitting in opposite directions, each transmission line 40 comprising two line wires, amplifiers for the transmission lines located at an intermediate station, means for interconnecting the ends of the transmission lines to form a loop circuit thereof, means at the intermediate 45 station and controlled from a terminal station over a circuit including a portion of the two line wires of one transmission line connected in parallel and a portion of the two-line-wires of the other transmission line 50 connected in parallel for increasing the amplification of the amplifiers so that power circulates over the loop circuit, and means at the intermediate station responsive to such circulating power for gradually decreasing the 55 amplification of the amplifiers until the circulation of power ceases.
11. In a telephone system in combination, a four-wire transmission circuit interconnecting two terminal stations and including 60 a pair of transmission lines for transmitting in opposite directions, amplifiers for the transmission lines located at an intermediate station, relays at each terminal station for interconnecting the ends of the transmission 65 lines to form a loop circuit thereof, means at the intermediate station controlled from a terminal station over a circuit including portions of the two transmission lines for increasing the amplification of the amplifiers so that power circulates over the loop circuit, and means in the circuit including portions of the two transmission lines for simultaneously rendering the interconnecting relays operative and the amplification increasing means effective, and means at the intermediate station responsive to the power circulating over the loop circuit for gradually decreasing the amplification of the amplifiers until the circulation of power ceases. 70
12. In a telephone system, in combination, a four-wire transmission circuit interconnecting two terminal stations and including a pair of transmission lines for transmitting in opposite directions, amplifiers for the transmission lines located at an intermediate station, relays at the terminal stations for interconnecting the ends of the transmission lines to form a loop circuit thereof, a control relay at each terminal station adapted when energized to cause the operation 90 of the connecting relays thereat, means at the intermediate station controlled from a terminal station for increasing the amplification of the amplifiers so that power circulates over the loop circuit, means at the intermediate station responsive to such circulating power for gradually decreasing the amplification of the amplifiers until the circulation of power ceases, and means in the 95 circuit including portions of the two transmission lines for causing the deenergization of the control relays at the terminal stations. 100
13. In a telephone system, in combination, a four-wire transmission circuit interconnecting two terminal stations and including a pair of transmission lines for transmitting in opposite directions, amplifiers for the transmission lines located at an intermediate station, relays at the terminal stations for interconnecting the ends of the transmission lines to form a loop circuit thereof, operating circuits for the interconnecting relays, a switch, primary control relays at each terminal station responsive to the actuation of the switch, a secondary control relay at each terminal station responsive to the restoration of the switch to normal position for closing the operating circuits of the interconnecting relays, means controlled by the 110 operation of the switch and the restoration thereof to normal position for increasing the amplification of the amplifiers so that power circulates over the loop circuit, and means responsive to such circulating power 115 for gradually decreasing the amplification of the amplifiers until the circulation of power ceases. 120
14. In a telephone system, in combination, a four-wire transmission circuit intercon- 125

necting two terminal stations and including a pair of transmission lines for transmitting in opposite directions, amplifiers for the transmission lines, connecting relays at the 5 terminal stations for interconnecting the ends of the transmission lines to form a loop circuit thereof, operating circuits for the connecting relays, a switch, a primary control relay at each terminal station energized 10 upon the actuation of the switch, a secondary control relay at each terminal station energized over a circuit including a contact of the energized primary control relay when the switch is restored to normal condition for 15 closing the operating circuits of the connecting relays, means for increasing the amplification of the amplifiers so that power circulates over the loop circuit, and means responsive to such circulating power for gradually decreasing the amplification of the amplifiers until the circulation of power ceases. 20

15. In a telephone system, in combination, a four-wire transmission circuit interconnecting two terminal stations and including 25 a pair of transmission lines for transmitting in opposite directions, amplifiers for the transmission lines connecting relays at the terminal stations for interconnecting the ends of the transmission lines to form a loop 30 circuit thereof, a switch, a primary control relay at each station energized upon the actuation of the switch, a secondary control relay at each station energized upon the restoration of the switch to normal condition 35 for controlling the connecting relays, means for increasing the amplification of the amplifiers so that power circulates over the loop circuit, means at each station and con-

trolled by the amplification increasing means for causing the deenergization of the primary control relays, means for gradually decreasing the amplification of the amplifiers until the circulation of power ceases, and means thereafter controlled by the amplification decreasing means for causing the de- 40 energization of the secondary control relays. 45

16. In a telephone system, in combination, a four-wire transmission circuit interconnecting two terminal stations and including a pair of transmission lines for transmitting in opposite directions, amplifiers for the transmission lines, connecting relays at each station for interconnecting the ends of the transmission lines to form a loop circuit thereof, operating circuits for the connecting relays, a switch, a primary control relay at each station energized upon the actuation of the switch, a secondary control relay at each station energized upon the restoration of the switch to normal condition 50 for completing the operating circuits, means for increasing the amplification of the amplifiers so that power circulates over the loop circuit, means responsive to such circulating power for gradually decreasing the 55 amplification of the amplifiers until the circulation of power ceases, and means controlled over a circuit including a portion of one of the transmission lines and a contact of one of the connecting relays for causing 60 the deenergization of the primary and secondary control relays. 65

In witness whereof, I hereunto subscribe my name this 8th day of July, A. D., 1919.

HORACE W. ULRICH.
